Primary Examiner — Marie D. Fast Horse*Assistant Examiner* — Josiah D. Parsons(74) *Attorney, Agent, or Firm* — N.V. Nederlandsch Octrooibureau; Catherine A. Shultz(57) **CLAIM**

The design for a remote control, as shown and described.

DESCRIPTION

FIG. 1 is a perspective view of a front of a remote control; FIG. 2 is a perspective view of a back of the remote control; FIG. 3 is a view from the bottom of the remote control; FIG. 4 is a view from the top of the remote control; FIG. 5 is a side view of the remote control; FIG. 6 is a side view of the remote control; FIG. 7 is a front plan view of the remote control; and, FIG. 8 is a back plan view of the remote control. The dash-dot broken lines depict a crop line that forms no part of the claimed design, while the broken dashed lines depict the cord portion of the remote control that forms no part of the claimed design.

1 Claim, 6 Drawing Sheets(56)
